CLAIM

We claim the ornamental design for a microwave transmission window assembly, as shown and described.

DESCRIPTION

FIG. 1 is a front side isometric view of a microwave transmission window assembly, according to one embodiment of the novel design.

FIG. 2 is a back side isometric view thereof.

FIG. 3 is a front side elevation view thereof.

FIG. 4 is a back side elevation view thereof.

FIG. 5 is a top plan view thereof.

FIG. 6 is a bottom plan view thereof.

FIG. 7 is a left side elevation view thereof.

FIG. 8 is a right side elevation view thereof.

FIG. 9 is a front side isometric view of a microwave transmission window assembly, according to another embodiment of the novel design.

FIG. 10 is a back side isometric view thereof.

FIG. 11 is a front side elevation view thereof.

FIG. 12 is a back side elevation view thereof.

FIG. 13 is a top plan view thereof.

FIG. 14 is a bottom plan view thereof.

FIG. 15 is a left side elevation view thereof; and,

FIG. 16 is a right side elevation view thereof.

The dashed lines in FIGS. 1-16 represent unclaimed environment and form no part of the claimed design.
